ASHER GOLDEN AND ELLIS M. POTTER, OF NEW YORK, N. Y.

STAMP AFFIXER.

Application filed April 13, 1922. Serial No. 552,091.

To all whom it may concern:

Be it known that we, ASHER GOLDEN and ELLIS M. POTTER, citizens of the United States, and both residents of the borough of Manhattan, city of New York, in the county of New York and State of New York, have jointly invented certain new and useful Improvements in a Stamp Affixer, of which the following is a specification.

10 This invention relates to a stamp affixer. The object of the invention is the production of a device, whereby postage stamps, labels and the like, which are connected in strips and with an adhesive on one side, can be easily detached from the strips and applied to envelopes or other articles.

15 A second object of the invention is the production of an affixer for adhesive tape which can easily be severed to required lengths and applied to packages, boxes and the like.

20 A third object of the invention is the production of means to moisten the object to which the stamps, labels or tape are to be affixed in place, and maintaining a roll of stamps, labels or tape therein free from moisture.

25 A fourth object of the invention is the production of an affixer that is portable, easily manipulated and that can easily be loaded with a roll of the strip of material, that is to be affixed to the object for which it is intended.

30 Other objects will be evident from the following description.

In the accompanying drawings Fig. 1 represents a side elevation of an exemplification of the improved stamp affixer, in this instance with a strip of postage stamps and envelopes; Fig. 2 shows a top plan view of the affixer; Fig. 3 indicates a section of Fig. 2 on the line 3, 3; and Fig. 4 is a section of Fig. 3 on the line 4, 4.

35 Referring to Figs. 1 to 4 the stamp affixer is shown to comprise a housing with a cylindrical compartment A, a reservoir B and a pocket C. Side walls 20 for the compartment A have formed therewith the extensions 21 for the reservoir B and the pocket C. Flanges 22 are formed with said extensions.

A cylindrical bottom wall 25 is fastened to the walls 20 and is continued to form the bearing plate 26 with the curved wing 28 having the tip end 29. The flanges 22

are fastened to the lower face of the bearing plate 26.

Guide flanges 30 with the flared inlet ends 31 are formed with the bearing plate 26 and form the guide channels 32.

60 A bottom plate 34 connects the lower edges of the extensions 21, the wall 25 and the plate 26, to form the reservoir B. A plate 35 with the perforations 36 and the rear wall 37 is inserted in the reservoir B 65 and forms the pocket C.

A cover D having the cylindrical wall 41, the opening 42 and the side walls 43 is hinged to wall 25 by means of the hinge 44. Locking lugs 45 with projections 46 70 extend from the walls 43. The projections 46 are adapted to lock with perforations 48 in the walls 20, when the cover D is locked in the closed position. A pin 50 with the journal ends 51 is supported in openings 52 and 53 formed respectively in the side walls 20 and 43.

75 A strip 54 of postage stamps or labels, adhesive tape and the like with an adhesive on one face thereof is wound in a roll 55 around the pin 50, and the latter is then supported in the openings 52 and 53 with one end of the strip 54 extending through the opening 42. The strip 54 is then located upon the bearing plate 26 with the adhesive side of the strip adjacent to said plate 26, and with the outer end of the strip extending slightly beyond the wing 28. Water is poured into the reservoir B through the openings 36 of the plate 35. A moistening 80 pad 56 is located in the pocket C and preferably folded with the fold 57 bearing up against the wing 28.

85 To use the affixer it is supported in an inclined position as shown in the drawings, so that the fold 57 of the moistening pad 56, bears upon the face of the envelope 62, or other object on the table 63, to which the strip 54 is to be attached. The fold 57 of the moistening pad is drawn over the surface of the envelopes 62 one after the other and the strip 54 is manually moved down on the bearing plate 26, to bring the stamps one after the other into contact with the envelopes. The stamps are then, one after the other, detached from the strip 54 and fastened to the envelopes.

100 The water in the reservoir B will flow through the perforations 36 and moisten the pad 56.

The method of applying stamps as described is applicable to label or adhesive tape that may be fastened to packages, boxes and other objects.

5 It is to be understood that various modifications may be made in the invention, and that the present exemplifications are only to be taken as illustrative and not limitative thereof.

10 Having described our invention what we desire to secure by Letters Patent and claim is:

1. In an affixer of the character described 15 the combination of a compartment, a cover having an opening in one of its walls hinged to a wall of the compartment, a pin for the roll of a strip of material journaled in the side walls of the compartment and cover, a guide plate extending from the compartment, guide flanges over the guide plate, a reservoir for a fluid below the guide plate and outside of the said compartment, and a pocket extending into the reservoir, said pocket having openings leading into

the reservoir and a moistening pad detachably supported in the pocket.

2. In an affixer of the character described the combination of a compartment, a cover having an opening in one of its walls hinged to a wall of the compartment, a pin for the 30 roll of a strip of material journaled in the side walls of the compartment and cover, a guide plate having a curved wing at its outer end extending from the compartment, guide flanges over the guide plate for the 35 strip of material, a reservoir for a fluid below the guide plate and outside of the said compartment, a plate with perforations and having a rear wall inserted in said reservoir constituting a pocket and a moistening pad 40 in said pocket.

Signed at the borough of Manhattan, city of New York in the county of New York and State of New York this 28th day of March A. D. 1922.

ASHER GOLDEN.
ELLIS M. POTTER.
